PAGE 2

Fig. 6

FIG. 1 is a top plan view of a ski pole basket, showing our new design.

FIG. 2 is a side elevational view thereof.

FIG. 3 is a bottom plan view thereof.

FIG. 4 is a sectional view, partly in elevation, taken along line 4-4 of FIG. 1.

FIG. 5 is a sectional view taken along line 5-5 of FIG. 1.

FIG. 6 is a top plan view of the ski pole basket shown in FIG. 1, wherein the radial arms have representations of snowflakes thereon, arranged in an alternating manner.

FIG. 7 is a top plan view of the ski pole basket of our design, wherein the radial arms have alternating concave and convex ends.

FIG. 8 is a side elevational view of the ski pole basket as shown in FIG. 7.

FIG. 9 is a bottom plan view thereof, wherein the radial arms are bevelled planes matching those on the upper surface and wherein the lower hub extension is omitted.

FIG. 10 is a sectional view of FIG. 7 taken along line 10-10.

The characteristic feature of our design resides in a hubbed ski pole basket having eight blunt end arms with the inner sides of said arms having a double bevel to form

a wedge-shaped edge. Said bevelled edges progressively increase towards the hub so that the surface plane of the arms presents a somewhat chisel shape, all as shown.

This application is a continuation of our co-pending applications Serial Number D. 63,870, filed February 8, 1961; Serial Number D. 63,871, filed February 8, 1961, and Serial Number D. 63,872, filed February 8, 1961, which are now abandoned.

We claim:

The ornamental design for a ski pole basket, substantially as shown and described.
